His Attorney.

UNITED STATES PATENT OFFICE.

EDWARD D. PRIEST, OF SCHENECTADY, NEW YORK, ASSIGNOR TO GENERAL ELECTRIC COMPANY, A CORPORATION OF NEW YORK.

COMMUTATOR FOR DYNAMO-ELECTRIC MACHINES.

1,349,854.

Specification of Letters Patent. Patented Aug. 17, 1920.

Application filed December 17, 1917. Serial No. 207,517.

To all whom it may concern:

Be it known that I, EDWARD D. PRIEST, a citizen of the United States, residing at Schenectady, in the county of Schenectady, 5 State of New York, have invented certain new and useful Improvements in Commutators for Dynamo-Electric Machines, of which the following is a specification.

My invention relates to an improvement 10 in commutators for dynamo electric machines, and particularly to an improved manner of connecting the armature leads to the segments of the commutator.

In the operation of certain dynamo electric machines, such as railway motors, trouble has been heretofore experienced 15 from the breaking of armature leads at the point of attachment to the commutator segments, due to the vibration of the leads, 20 causing them to bend back and forth until they finally break in two.

The object of my invention is to reduce 25 to a minimum the vibration of the leads, so as to render their breakage less likely, and at the same time, to provide means whereby the machine will still be operative even though one of the leads does break.

My invention will be more fully explained 30 in connection with the accompanying drawing, in which Figure 1 shows a sectional view of a portion of a commutator arranged in accordance with my invention and Fig. 2 shows a modification thereof.

Referring to the figures of the drawing, 1 35 is a commutator segment of a commutator 2 of a dynamo electric machine provided at one end with the usual lead receiving slot in which a pair of armature leads 3 are fastened. The end of the segment, to which 40 the leads are fastened, is cut away, either by chamfering as illustrated at 4 in Fig. 1, in which case the chamfer is at any angle to the direction in which the leads enter the segment, or by the step arrangement as illustrated at 5 in Fig. 2. By either of these 45 arrangements the leads will be attached to the segments in different transverse planes. Consequently they will be of different lengths and their natural period of vibration will be different, so that they will no longer tend to vibrate together. In this way 50 the vibration of the leads will be damped out to a considerable extent. The tend-

ency of both leads to break at the same instant is thus greatly reduced. This is especially true of the construction shown in Fig. 1, because, in addition to the difference in lengths of the two armature leads, the line at which breakage naturally tends to take place, is along the line of the 60 chamfering which involves longer cross sections of the leads where they are joined to the commutator segment, the point of bending also being less well defined as the leads enter the segment on a sloping line. 65

In order to still further reduce the tendency of the leads to break, and, at the same time, have the machine still operative in case one of the leads does break, I connect the two leads together, both mechanically 70 and electrically and independently of the commutator, by a band 6 soldered around them. The band 6 is spaced a sufficient distance from the commutator to permit of the usual flexibility at the point of connection to the segment. 75

With this arrangement of the segments and leads, the tendency to breakage is still further reduced, for the reason that the band 6 will tend to further reduce the 80 vibration of the leads because one lead tends to support the other to a certain extent, and at the point where one wire is apt to break off, the other is in a position to bend. Should one of the leads break, the operation 85 of the machine will not be effected, since the band 6 connects the armature coils independently of the commutator and there will be no open circuit unless both leads break.

I have illustrated and described my invention as embodied in what I now consider the preferred forms, but the arrangement is susceptible of further modification and I therefore aim in the appended claims to cover all such modifications as lie within the 95 scope of my invention. 90

What I claim as new and desire to secure by Letters Patent of the United States, is:

1. In a commutator for dynamo electric machines, a commutator segment provided at one end with a lead receiving slot, a pair of armature leads fastened therein, said segment being cut away at the point of attachment in such a manner that said leads enter the segment at points in different 100 transverse planes, and means for mechani- 105

cally and electrically connecting said leads together adjacent the end of the commutator segment but independent thereof.

2. In a commutator for dynamo electric machines, a commutator segment provided at one end with a lead receiving slot, a pair of armature leads fastened therein, and

means for mechanically and electrically connecting said leads together, said means being independent of and spaced from the end of the commutator segment.

In witness whereof, I have hereunto set my hand this 14th day of December 1917.

EDWARD D. PRIEST.
